(57) **CLAIM**

The ornamental design for a magnetic charging cable for a mobile device, as shown and described.

DESCRIPTION

FIG. 1 is a perspective view of a first embodiment of a magnetic charging cable for a mobile device according to our design;

FIG. 2 is a front view of the magnetic charging cable of FIG. 1;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a magnetic charging cable for a mobile device according to our design;

FIG. 9 is a front view of the magnetic charging cable of FIG. 8;

FIG. 10 is a rear view thereof;

FIG. 11 is a right side view thereof;

FIG. 12 is a left side view thereof;

FIG. 13 is a top view thereof; and,

FIG. 14 is a bottom view thereof.

Features of the magnetic charging cable that are shown in broken lines are for illustrative purposes and form no part of the claimed design.

The magnetic charging cable is shown with a symbolic break in its length. The appearance of any portion of the article between the break lines forms no part of the claimed design.
